UNITED STATES PATENT OFFICE

110,096

DESIGN FOR AN ADVERTISING FIGURE

Ralph W. Leavenworth, Shaker Heights, Ohio, assignor to The National Screw & Manufacturing Company, Cleveland, Ohio, a corporation of Ohio

Application February 25, 1938, Serial No. 75,397

Term of patent 14 years

To all whom it may concern:

Be it known that I, Ralph W. Leavenworth, a citizen of the United States and a resident of Shaker Heights, in the county of Cuyahoga and State of Ohio, have invented a new, original, and ornamental Design for an Advertising Figure, of which the following is a specification, reference being had to the accompanying drawing, forming a part thereof, in which

Fig. 1 is a perspective view of the advertising figure embodying my new design;

Fig. 2 is a side view of the same; and

Fig. 3 is a fragmentary front elevational view showing the head of the figure in enlarged detail.

I claim:

The ornamental design for an advertising figure substantially as shown.

RALPH W. LEAVENWORTH.
